[57] **CLAIM**

The ornamental design for an advertisement pillar or similar article, as shown and described.

DESCRIPTION

FIG. 1 is a front elevational view of an advertisement pillar or similar article showing my new design, the rear being identical thereto;

FIG. 2 is a top plan view thereof, the bottom being plain and unornamented;

FIG. 3 is a side elevational view thereof, the opposite side being identical thereto;

FIG. 4 is a front elevational view of a second embodiment of that shown in FIG. 1, the rear being identical thereto;

FIG. 5 is a top plan view thereof, the bottom being plain and unornamented;

FIG. 6 is a side elevational view thereof; the opposite side being identical thereto;

FIG. 7 is a front elevational view of a third embodiment of that shown in FIG. 1, the rear being identical thereto;

FIG. 8 is a top plan view thereof, the bottom being plain unornamented;

FIG. 9 is a side elevational view thereof, the opposite side being identical thereto;

FIG. 10 is a front elevational view of a fourth embodiment of that shown in FIG. 1, the rear being identical thereto;

FIG. 11 is a top plan view thereof, the bottom being plain and unornamented; and

FIG. 12 is an elevational view thereof, the opposite side being identical thereto.
